(57) **CLAIM**

The ornamental design for a wireless air vent mounting charger, as shown and described.

DESCRIPTION

FIG. 1 is a front view of our new design for a wireless air vent mounting charger;

FIG. 2 is a right side view thereof;

FIG. 3 is a left side view thereof;

FIG. 4 is a rear view thereof;

FIG. 5 is a top view thereof;

FIG. 6 is a bottom view thereof;

FIG. 7 is a left rear top perspective view thereof;

FIG. 8 is a right rear top perspective view thereof;

FIG. 9 is a left rear bottom perspective view thereof;

FIG. 10 is a right rear bottom perspective view thereof;

FIG. 11 is a right front top perspective view thereof;

FIG. 12 is a left front top perspective view thereof;

FIG. 13 is a right front bottom perspective view thereof; and,

FIG. 14 is a left front bottom perspective view thereof.
